DESIGN FOR A SIGNALING DEVICE

John Jurgen Henry Muller, Jr., Woodmont, Conn.

Application January 23, 1940, Serial No. 89,646

Term of patent 3½ years

To all whom it may concern:

Be it known that I, John Jurgen Henry Muller, Jr., a citizen of the United States, residing in Woodmont, in the county of New Haven and State of Connecticut, have invented a new, original, and ornamental Design for a Signaling Device, of which the following is a specification, reference being had to the accompanying drawing, forming part thereof.

In the drawing:

Fig. 1 is a front elevational view of a signaling device, showing my new design, and

Fig. 2 is a side elevational view thereof.

I claim:

The ornamental design for a signaling device, as shown.

JOHN JURGEN HENRY MULLER, JR.
